UNITED STATES PATENT OFFICE.

DAVID J. SIMPSON, OF PITTSBURG, ASSIGNOR OF ONE-HALF TO GEORGE C. CORKEN AND HAWDON MARSHALL, OF ALLEGHENY COUNTY, PENNSYLVANIA.

ELECTRIC COUPLING FOR HOSE-PIPES.

SPECIFICATION forming part of Letters Patent No. 396,176, dated January 15, 1889.

Application filed April 16, 1888. Serial No. 270,833. (No model.)

To all whom it may concern:

Be it known that I, DAVID J. SIMPSON, of Pittsburgh, in the county of Allegheny and State of Pennsylvania, have invented certain new and useful Improvements in Electric Couplings for Hose-Pipes; and I do hereby declare the following to be a full, clear, and exact description of the same, reference being had to the accompanying drawings, forming a part of this specification, and to the figures and letters of reference marked thereon.

This invention relates to a new and improved electric coupling or circuit-closer, designed more especially for use in connection with the detachable coupling-sections commonly employed for uniting sections of hose-pipe, and employed for automatically closing an electric circuit or circuits through the coupled hose-pipe, which circuit is or may be employed for sending and receiving signals or operating electric devices of any desired character.

The principal object of my present invention is to so construct and organize the electric coupling and apply it to the section of the hose-coupling that the circuit wires or conductors carried by or attached to one section of hose will be automatically placed in electric contact with the circuit wire or wires of another section of hose in and by the act of coupling said hose-sections together. At the same time the insulation of the electric circuit thus formed will be preserved and maintained in and between the hose-couplings to prevent grounding or short-circuiting the line at that point.

To this end my said invention consists in the novel construction, arrangement, and combination of parts, hereinafter fully described, and pointed out in the claims.

In the accompanying drawings, Figure 1 is a side elevation, partly in section, illustrating two coupling-sections with my improved electric coupling applied thereto. Fig. 2 is an end or face view of one coupling, and Fig. 3 is a similar view of the co-operating coupling.

Similar letters of reference in the several figures indicate the same parts.

The letters A and B designate the two co-

operating sections of a hose-coupling secured to the ends of the hose-sections in the usual manner. The particular variety of coupling represented, and in connection with which my invention is illustrated, comprises the section 55 A, with threaded extension *a*, and section B, carrying internally-threaded collar *b*, mounted upon socket *b'*, and adapted to rotate thereon in the usual manner. The end of hose-pipe C is inserted and secured within the rear or 60 socket ends of the two sections A B.

The coupling A B, as a means for connecting and disconnecting the ends of hose-pipe, is too well known to require more detailed explanation, and is referred to merely as illustrative of a type of hose-coupling such as may be employed in connection with my improvements, it being understood that equivalent forms of couplings may be substituted for that shown.

The coupling-sections A B are, as usual, of metal. Each hose-section contains two or more insulated wires, D D', preferably interposed between and held in place between the layers composing the hose-pipe, said wires being 75 conveniently inserted during the process of manufacturing the hose.

The object in employing two conductors is to provide a return-wire, thus forming a complete metallic circuit through the hose.

One wire, D', is connected at opposite ends of each hose-section to the metallic couplings A B, so that when the coupling-section A of one length of hose is attached to section B of another length of hose, as by screwing the 85 collar *b'* upon the threaded extension *a*, the wires D' will be electrically connected to form one line or branch of the circuit. The other or return-line is formed by connecting the wires D together, and to accomplish this and at the 90 same time preserve the necessary insulation the following arrangement is adopted: One of the coupling-sections—A, for example—is provided with a metallic ring, 1, insulated from the metallic portion of the coupling and forming the whole or portion of the ring-seat, against which the rubber gasket or other non-conducting packing bears for forming a watertight joint between the sections A B when 95 coupled. One end of the wire D is attached 100

- to this ring 1 and the other end to a metallic contact, 2, projected upon or over the face of the gasket or packing 3, held in the opposite section, B, so that when the coupling-sections 5 A B are screwed together and the gasket or packing 3 is grasped or clamped between them, as in forming the water-tight joint, the contact 2 on one section will be pressed and held in electrical contact with the ring or contact-piece 1 on the opposite section, and as these contacts are insulated from the metallic coupling-sections the line through wires D is completed and at the same time held electrically insulated from the line D'. It will thus be seen that whenever the sections A and B are coupled and united to form a tight joint the electric contact necessary to effectually close the circuits through wires D D' is simultaneously and automatically made. It will be observed, moreover, that as applied to the particular form of coupling shown another and further advantage is secured. It is well known that one of the most frequent causes of failure in making a proper circuit-connection between electric conductors, especially such as are exposed to atmospheric and other influences, as in the present example, is the formation of a deposit upon the surface of low conducting capacity, so that when the conductors are brought together but an imperfect electrical connection is formed. In the present instance, however, this defective action is overcome or avoided by causing the contacts (in the one case the couplings themselves and in the other the ring 1 and contact 2) to move or rub more or less together, thereby destroying or removing sufficient of the oxide or coating to insure a good electric contact.
- Another and further improvement consists in the provision made for preventing short-circuiting or grounding of the electric circuit through the water or other conducting material passing through the hose. It is well known that water, although a poor conductor of electricity, will nevertheless serve to establish electric connection between metallic conductors; hence if the terminals or contacts 1 2 of wires D, are exposed to the water passing through and in contact with the metallic portions of couplings A B a portion of the current passing through the circuit-wires D D' will be short-circuited at that point.
- Although the quantity of electricity passing from wire D to wire D' at each coupling may be very small, when a large number of couplings are employed it will amount to considerable in the aggregate. Moreover, the leakage thus effected, although slight, is continuous and will suffice in time to exhaust or run down the battery, thereby seriously interfering with or preventing the use of the signal-circuit when most required. To overcome this defective action and insure complete insulation of at least one of the circuit-wires in the couplings, (it being only necessary that one of the parallel wires should be insulated

to prevent short-circuiting,) the insulation 5, supporting and carrying ring 1, is secured within or upon the end of the threaded extension *a* and extended up the inner face of the ring or conductor 1 flush, or nearly so, with the outer face of said conductor. The co-operating conductor or contact 2, carried by coupling-section B, is passed through an insulated section, 6, inserted within said coupling and passes through an opening formed in the rubber gasket, the end of said contact 2 being bent down or extended laterally over the exposed face of the gasket. When, now, the coupling-sections A B are united and the gasket of rubber or other flexible non-conducting material is clamped between the ring-seats on the opposite sections, not only is the fluid prevented from escaping from the coupling at this point, but it is likewise prevented from coming in contact with the conductors 1 and 2, the one being embedded in the gasket and the other covered on the inside, at least, by the gasket overlapping or being pressed against the insulation 5. The insulation, it will be seen, may be extended up on both the inner and outer sides of the ring, and so leave only the face exposed, which latter will be entirely covered by the gasket and all access of water thereto from any direction prevented.

By employing an annular conductor, 1, co-operating with one or more contacts, 2, and uniting them through the gasket or packing-ring, the insulated line D is sure to be connected electrically whenever the coupling-sections A B are united to form a water-tight joint, and no special fitting or skill in manipulation is required to complete the electric circuit, as this is accomplished automatically in the act of coupling, as usually performed.

As is obvious, it is not essential that the annular contact 1 be affixed to the section A, entering section B, and the contact 2 located in the latter, as the relative positions may be reversed.

Among the numerous advantages of my improved electric coupling is its simplicity and effective action not alone in making the connections between the conductors, but in preserving the insulation and preventing short-circuiting or bleeding the battery. Moreover, the electrical attachments are at all times accessible and can readily and quickly be applied and adapted to the ordinary forms of hose-couplings now in use, as is well indicated in the drawings, the only manipulations required to effect the attachment being the insertion of the insulating ring-bearing conductor 1 within the mouth or open end of one section, A, and drilling a hole for the passage of the insulated wire D, and the drilling of a hole or insertion of an insulating-support for the stem of conductor 2 in section B.

The wires D are preferably protected by an insulating-covering, besides being further protected by the material of which the hose is composed, said wires being introduced between layers or coatings of the hose, so that

each wire is completely insulated and protected throughout its entire length.

If desired, instead of connecting the line-wires D' directly to the coupling-sections, 5 they may be connected electrically in a manner similar to the line-wires D—that is to say, duplicate contacts 2, one for each line, may be provided for one section, B, and the contact plate or ring 1 divided, the two sections 10 insulated, and the wires D D' each connected to one section, so that when the coupling-sections are secured together one circuit-wire will be closed through contacts 1 and 2 and the other through contacts 1^x and 2^x, as indicated by dotted lines Figs. 2 and 3.

Having thus described my invention, what I claim as new is—

1. In combination with the sections A B of a coupling such as described, provided with 20 ring-seats and an interposed non-conducting gasket, a contact-electrode carried by one section of the coupling and connected with the line through the gasket, and an opposing contact secured to the other section of the coupling 25 in position to engage the first-mentioned contact when the gasket is clamped between its seats, said contacts and connecting-wires being insulated from the metallic couplings, substantially as described.

2. In combination with the detachable sections of a hose-coupling such as described, an insulated conductor or contact carried by one section and projected upon the face of the gasket interposed between and forming the 35 water-tight joint, and an annular contact or conductor forming the ring-seat on the opposite coupling-section, said ring-seat being insulated from the coupling-sections with circuit-wires connected to each of said contacts, 40 substantially as and for the purpose set forth.

3. In combination with the separable sections of a hose-coupling such as described, an electric contact mounted upon but insulated from one section of the coupling and projected 45 through the non-conducting elastic gasket, and an opposing electric contact mounted upon but insulated from the co-operating section of the coupling and engaging the first-mentioned contact and the gasket to close the 50 circuit and protect the joint, substantially as and for the purpose set forth.

4. In combination with the separable metallic sections of a hose-coupling such as described, provided with clamping devices and 55 an elastic non-conducting gasket interposed

between seats within the two sections, a line-wire connected to the metallic sections of the couplings, and a second or return wire connected to contact plates or terminals insulated from and supported within the coupling-sections, one of said contacts forming part of the gasket-seat on one section and the other opposing contact projecting upon the side of the gasket facing the opposite section, so that when said coupling-sections are united one 60 line will be closed through the coupling and the other between the gasket and its seat, substantially as and for the purpose set forth.

5. In combination with the sections A B, the hose attached thereto and the insulated 70 wires D D', forming parts of an electric circuit, the wire D', attached to and connected through the metallic sections A B, the insulating-support inserted in section A and provided with annular contact 1, the gasket, and 75 the contact 2, passing through said gasket, said contacts 1 and 2 being connected to wires D', insulated from the metallic coupling-sections, as and for the purpose set forth.

6. In a hose-coupling such as described, 80 comprising separable sections A B, an interposed non-conducting gasket, and means for holding the two sections together and clamping them upon the gasket, a contact plate or ring, 1, insulated from but sectioned to one of 85 said coupling-sections in line with the gasket and provided with an insulating lining or covering, a contact or conductor, 2, carried by the opposite coupling-section insulated from the latter and projected upon the exposed face of 90 the gasket, said gasket co-operating with the insulated lining of contact 1 to form a tight joint and exclude water or other liquid-conducting medium from contacts 1 and 2, as set forth.

7. In a hose-coupling such as described, containing separable sections A B, the insulated ring bearing annular contact 1, inserted 100 in section A, the wire D, passing through section A and attached to ring 1, the non-conducting elastic gasket fitting over the annular contact 1 and interposed between the sections, and the contact 2, passing through the gasket in position to engage contact 1 when the sections A B are connected, as and for the 105 purpose set forth.

DAVID J. SIMPSON.
